UNITED STATES PATENT OFFICE.

EDWARD MAYBERRY SMITH, OF KANSAS CITY, MISSOURI, ASSIGNOR OF ONE-THIRD
TO BETTIE WADDELL SMITH, OF KANSAS CITY, MISSOURI, AND ONE-THIRD TO
ROBERT EMMART SMITH, OF ST. LOUIS, MISSOURI.

TIME-CALCULATING MACHINE.

1,377,856.

Specification of Letters Patent. Patented May 10, 1921.

Application filed July 14, 1916. Serial No. 109,400.

To all whom it may concern:

Be it known that I, EDWARD MAYBERRY SMITH, a citizen of the United States, residing at Kansas City, in the county of Jackson, son and State of Missouri, have invented certain new and useful Improvements in Time-Calculating Machines, of which the following is a full, clear, and exact description, such as will enable others skilled in the art to which it appertains to make and use the same.

The invention relates to time calculating machines for computing interest and seeks to provide a simple and efficient form of machine that will mechanically indicate the time in days intervening between the initial and terminal dates of bonds, notes, accounts and the like upon which it is desired to ascertain the amount of interest.

The present invention seeks to provide an improved machine that will indicate the number of days from an initial to a terminal date inclusive for any given time and also indicate the initial from the terminal date when the number of days are known, and the terminal date from the initial date. With these and other objects in view the invention consists in the features of construction, parts, combinations, manipulations, and arrangements of parts hereinafter set forth and more particularly pointed out in the appended claims, the accompanying drawings illustrating an application of the invention.

In the drawings:

Figure 1 is a view of the interest calculating machine from the usual operating position of the operator with the multiplying and dividing machine inclosed and not in operative position.

Fig. 2 is an end view of the interest calculating machine closed as in Fig. 1.

Fig. 3 is a sectional view of the machine closed, taken on line 3-3 of Fig. 1.

Fig. 4 is an end view of the machine with the multiplying and dividing machine in operative position.

Figs. 5 and 6 are fragmentary views taken on line 5-6 of Fig. 3.

Figs. 7 and 8 are fragmentary views of the interest calculating machine, the views extending from opposite ends to and past the center of the machine and overlapping, the

column of each view over Fig. 7 being the same.

The inclosing casing comprises upper wall 17, lower wall 18, rear wall 19, front wall 20, intermediate wall 21, end walls 22 and 23, and doors 24, the doors being hinged by hinges 25 to the respective end walls.

The front wall 20 is curved at 26 and extends horizontally to 27 where it meets the upper wall 17, the front wall being provided with the slot or elongated opening 28, while the upper wall curves from 27 to 29 and the greater portion of this distance the wall is divided into bars 30 forming the openings 31 therebetween, the bars being provided with the numerals one to three hundred and ninety inclusive and representing the number of days reckoning from the opening 32 as the initial day, the dates appearing in the openings 31 being hereinafter explained.

The elongated opening 28 is for the purpose of reading certain data and formulatator tables that can be successively or alternately displayed therethrough but not claimed in the present application.

The roller 33 is provided with the journals 34 and 35 rigid therewith which are journaled in the end walls 22 and 23 respectively, the knob 36 being rigid with the roller and journaled end thereof 34.

Projecting from the roller 33 and rigid therewith is the brake ring 38 which is held in contact with the end wall 22 by the compression spring 39, the latter bearing against the shoulder 40 of the roller and against the end wall 23, the brake ring being sufficient to prevent the roller from turning excepting when the knob 36 is pressed toward the end wall 22 and the ring released therefrom.

The roller 41 is journaled on the shaft 42, the latter having a square end 43 fitting in the end wall 22 to prevent the shaft from turning, the opposite end of the shaft fitting the end wall 23.

Secured to the shaft 42 at 44 and to the roller at 45 is the winding spring 46 which will allow the roller to turn several revolutions, the spring always exerting a force to return the roller to normal position.

The time computing sheet 47 is secured to the roller 33 and the roller 41 so that it can be rolled from one to the other and return,

the object being to roll the sheet to and fro to place the desired dates on the sheet in alinement with the numerals on the bars 30 so that the numeral on the bar adjacent the 5 desired date and on the right hand thereof can be noted. It is understood that by pressing the knob 36 toward the wall 22, the roller 33 can be turned in either direction and the time computing sheet 47 wound 10 on the roller 33 and unwound from the roller 41, the spring 46 operating to rewind the sheet on the roller 41 as it is unwound from the roller 33, so that any date on the computing sheet can be displayed in the 15 openings 31, with the desired dates thereon in alinement with certain numerals on the bars 30.

The machine 61 is of the usual type for multiplying, dividing, subtracting, and 20 adding, and is employed principally for multiplying and dividing as these are the only computations necessary to determine all the usual amounts of interest.

To calculate the interest for a given time 25 on a given amount, the initial date on the time computing sheet 47 is placed in the opening 32, the date appearing in this position of the drawing in Fig. 7 being Dec. 31, 1915, the terminal date is then noted and 30 the numerals to the right thereof and in alinement therewith on the adjacent bar 30 is read, this last number being the number of days from the initial to the terminal date inclusive.

35 It will be noticed that each bar 30 contains thirty numbers so that periods of thirty, sixty, and ninety days and other multiples of thirty will read in alinement with the initial date in the opening 32, this being 40 very advantageous as most interest dealt with in banks and the like runs thirty days or in multiples of thirty days.

Should the date of maturity be known the 45 number of days is instantly found by glancing to the right and noticing the position of the maturing date, the number of days on

the bar 30 to the right of the maturing date and in alinement therewith always representing the number of days for which the interest is to be computed.

Should the interest desired be for a period of one year from date, the date Dec. 31, 1916, will be found in the column over the numerals 13 and the days will be 366 as indicated.

Interest is usually figured for a period of one year from date, one month or a given number of months, a given number of months and days, a given number of days, to a specified date after the initial date, or 6 on demand, the time calculating sheet serving equally well and instantly indicating the number of days in each and every condition.

What I claim is:—

In a time calculating machine for computing interest, a series of columns of dates, each of said dates naming a month, a day of the month and a certain year, numerals running successively from 1 to 390, inclusive, and arranged parallel with said 70 columns of dates with thirty of the numbers indicated by said numerals to each column of said dates, and means to display said dates so that said numerals, counting from and not including the initial date, will instantly and 75 simultaneously indicate the day the month and the year of terminal dates of thirty days, sixty days, and ninety days following the initial date, and multiples of thirty days, sixty days, and ninety days from and after 80 the initial date and simultaneously indicate any and all terminal dates including the year from and after the initial date to and including three hundred and ninety days from the initial date. 85

In testimony whereof I affix my signature in the presence of two witnesses.

EDWARD MAYBERRY SMITH.
